[57] CLAIM

The ornamental design for a security box, as shown and described.

DESCRIPTION

FIG. 1 is a perspective view of a security box showing my new design;

FIG. 2 is a perspective view thereof showing a lid thereof in an opened position;

FIG. 3 is a front elevational view thereof;

FIG. 4 is a rear elevational view thereof;

FIG. 5 is a top view thereof;

FIG. 6 is a top view thereof showing a lid thereof in an opened position; and,

FIG. 7 is a left side elevational view thereof with the right side being a mirror image thereof.

The broken line showing of the state of Pennsylvania with letters and leaves in FIGS. 1, 2, and 3, the legs in FIGS. 1, 2, 3, 4, and 7, and the handles in FIGS. 1, 2, 3, 4, 5, and 7 is for illustrative purposes only and forms no part of the claimed design.

FIG. 1

FIG. 2

FIG. 3

FIG. 4

FIG. 5

FIG. 6

FIG. 7
